J. A. SEEGER

REFRIGERATOR

Filed May 21, 1921

Inventor:

John A. Seeger.
By Howard Frick
his Attorney.

UNITED STATES PATENT OFFICE.

JOHN A. SEEGER, OF ST. PAUL, MINNESOTA, ASSIGNOR TO SEEGER REFRIGERATOR COMPANY, A CORPORATION OF MINNESOTA.

REFRIGERATOR.

Application filed May 21, 1921. Serial No. 471,352.

My invention relates to refrigerators and has for its object to provide a refrigerator, the entire interior of which may be enameled to form a perfectly sanitary construction.

Another object of the invention is to provide a device for preventing the walls of the ice chamber adjacent the food compartment from sweating and causing moisture to drip from the same.

Another object is to provide a separate food compartment and ice chamber with enameled interior surfaces and to mount the same with their walls in spaced relation to one another to form a sweat proof and sanitary construction.

Heretofore it has been practically impossible to construct a refrigerator in which the entire interior including the ice chamber and food compartment have been formed of enameled iron due to the sweating occasioned within the food chamber. In my invention I have overcome this by forming the lining in separable portions so as to provide the entire walls surrounding the ice chamber of double thickness with some suitable insulating material such as an air space, wood or the like, interposed between the same in order that the transfer of heat from the outer to the inner wall of the ice chamber by conduction is prevented.

The full objects and advantages of my invention will appear in connection with the detailed description thereof and are particularly pointed out in the claims.

In the drawings, illustrating the application of my invention in one form:—

Fig. 1 is a front elevational sectional view of a refrigerator showing my invention applied thereto.

Fig. 2 is a side sectional view similar to Figure 1 of a modification of the invention shown in Figure 1.

Fig. 3 is a fragmentary sectional view similar to Fig. 1 of a modification of the invention shown in Figure 1.

In Figures 1 and 2, I have shown a refrigerator formed with an outer casing A having a top 10, side walls 11 and 12, a bottom 13, a front 14 and a back 32. These walls may be of any suitable construction for insulating and supporting the interior of the refrigerator. The front wall 14 of casing A is provided with openings 25 and 26 by means of which access is had into the

interior of the refrigerator. These openings may be closed by suitable closure members or doors 27 and 28 adapted to close tight over the openings 25 and 26 and to insulate the interior of the refrigerator from the exterior.

Within the interior of the refrigerator is provided two separate linings or shells B and C, which are arranged in relation to one another as best shown in Figure 1. Shell C is substantially L shaped and is provided with a short top 15 positioned adjacent the casing member 10, a bottom 16 positioned on the casing member 13, and a member 17 which runs parallel with the bottom 16 and which in conjunction with the portion of the bottom 16 forms the lower leg of the L. Shell C is further provided with a side member 18 which lies against the side wall 11 and with an upstanding side member 19 which in conjunction with the upper portion of the side 18 forms stem of the L. An end wall 20 positioned adjacent wall 12 of the casing A encloses the end of the leg of the L. At the rear of shell C the same is formed with a back 21 which is of L shaped formation and at its front with a similarly formed L shaped front member 22 which is provided with openings 24 to register with the openings 26 in the front 14 of the casing A.

In the angle of the L shaped shell C is positioned the shell B which is of rectangular shape having a top 29 and an end wall 30 lying adjacent the walls 10 and 12 of the casing A and having a back 31 and a front 33 situated adjacent the back wall 32 and front wall 14 of said casing. This front wall 33 is formed with an opening 23 adapted to register with the opening 25 in the front wall 14 of casing A as is clearly shown in Figure 2, whereby access may be had into the ice compartment of the refrigerator. Shell B is further provided with a side wall 34 positioned parallel to the side wall 19 of shell C and with the bottom 35 positioned above the top wall 17 of said same shell C.

In the form of the invention shown in Figures 1 and 2 the shell B forming the ice chamber is made of such a shape and size that when the same is positioned within the refrigerator casing A the walls 19 and 34 and the top and bottom members 17 and 35 of said shells are positioned in spaced relation.

tion to one another as clearly shown in Figure 1. For holding shell members B and C in proper relation to one another within the refrigerator casing A the space between the walls 19 and 34 and between the top 35 and bottom of said shell members may be filled with a wood or other insulating member 36 which extends within the same and which may completely or partially fill the space as desired.

To provide a passageway for the circulation of the air within the refrigerator I form an opening 37 in the side walls 19 and 34 of shell members C and B which opening 15 extends completely across the refrigerator and is positioned immediately below the tops 15 and 29 thereof. This opening is formed by turning over a flange 38 on the metal of the side 19 which engages a corresponding 20 flange 39 formed on the wall 34 and adapted to cooperate therewith to form a closed wall extending perimetricaly around said opening 37. In a similar manner the top 17 and bottom 35 are provided with an opening 42 25 which is formed by an upstanding continuous flange 40 adapted to cooperate with a corresponding turned over lip or flange 41 formed on the bottom member 35. To prevent the water of liquefaction of the ice 30 from discharging through the opening 42 into the food compartment I preferably form the lip 41 which extends completely around this opening raised above the plane of the surface of bottom 35 so as to form a 35 ridge to prevent the overflow through said opening.

For the purpose of draining the ice chamber of water I preferably slope the bottom member 35 of shell B towards the front wall 40 33 and side wall 34 of said shell. At the lowest point of this bottom 35 I provide a discharge pipe 43 passing through the insulating member 35 and the top 17 of shell C. This discharge pipe may be connected 45 by a tube 44 to any suitable trap 45 by means of which the water may escape from the refrigerator through a discharge pipe 46. The trap 45 has not been shown in detail in the drawings, though it can be clearly understood that any suitable form of trap 50 adapted to refrigerators may be used for this purpose.

In Figure 3 I have shown a slight variation in the form of refrigerator shown in 55 Figure 1. In this type the insulating medium 36 shown in Figure 1 is dispensed with and a number of spacers 47 employed which are attached to the side walls 19 and 34 and the top 17 and bottom 35 of members C and B, to hold the same in proper relation to one another. With this construction an air space 48 is provided which may be continuous or interrupted depending upon the size and formation of the spacer member 47. 60 The exact formation of this air space, how- 65

ever, is unimportant as far as the functioning of the parts is concerned.

In both of the forms of my invention shown in the drawings I prefer to coat the interiors of both the food compartment and ice chamber with enamel to make the refrigerator perfectly clean and sanitary. It can be readily understood that this coating of enamel can be baked on or applied by any of the ordinary methods now in use. In this 70 way the inside of each of the containers is enameled and the parts so arranged that the corresponding unfinished exterior surfaces of the same are completely hidden from view so as to expose nothing but the clean 75 enamel.

The advantages of my invention are manifest. The two compartments can be independently constructed and enameled on the interior of the same as if a single container 80 were used. In this manner the construction of the device is still held exceedingly simple and the parts prepared in the usual manner. After the same have been enameled the parts are assembled with the walls 85 thereof in spaced relation to one another. In this manner all of the unfinished surfaces are hidden and the walls adjacent the ice chamber are insulated from the food compartment so that sweating on the interior walls of the food compartment is eliminated. In this manner an exceedingly clean 90 and sanitary refrigerator is provided in which sweating is entirely eliminated.

In accordance with the patent statutes I 100 have described the principles of operation of my invention, together with the apparatus which I now consider to represent the best embodiment thereof, but I desire to have it understood that the construction shown is 105 only illustrative and that the invention can be carried out by other means and applied to uses other than those above set forth within the scope of the following claims.

I claim:—

1. A refrigerator comprising an L-shaped shell having an opening across the upper portion of the vertical wall of said L-shaped part and a second opening formed across the center of the horizontal wall of the leg of said L-shaped part, flanges formed on said shell and extending outwardly from said shell around both of said openings, a rectangular shell adapted to fit into the angle of said L-shaped part having openings registering with the openings of said L-shaped part, a grooved seat formed along the edge of said lowermost opening in said rectangular shell adapted to seat upon the edge of the flange of said L-shaped part corresponding with the opening therein and a telescoping member formed around said upper opening.

2. A refrigerator comprising an L-shaped shell, an opening across the upper portion 130

of the vertical wall of the L-shaped shell, a flange extending outwardly from said shell and around said opening, a second opening extending across the center of the horizontal wall of the leg of said L-shaped shell, a second flange turned upwardly from said shell and extending around said opening, a rectangular shell adapted to fit into the angle of said L-shaped shell, having openings registering with the openings of said L-shaped shell, a flange formed around the opening in the rectangular shell registering with the first named opening in said L-shaped shell and adapted to envelope the corresponding flange on the L-shaped shell, and an upwardly turned U-shaped lip formed around the second opening in the rectangular shell integral with said rectangular shell having a depending flange adapted to fit into the interior of the corresponding flange of said L-shaped shell.

3. A refrigerator comprising, a casing, a lining having a substantial L-shape, openings in said lining, flanges extending integral from said lining at said openings, the entire inner surface of said lining being enameled, an ice compartment having openings with integral flanges projecting therefrom adapted to telescopically register with the openings in said L-shaped compartment, and the entire inner surface of said ice compartment being enameled whereby the entire inner surface of said L-shaped compart-

ment is enameled and adapted to unite through said registering openings of the respective parts of the lining to provide a smooth, uniform surface throughout the entire inner part of said refrigerator for cleanliness.

4. Refrigerator linings including, an L-shaped portion, a rectangular portion, registering flanges integral with the lining forming openings in each of said portions to provide communicating openings to the respective lining portions, and an enameled surface over the entire inner face and connecting openings of each of said portions adapted to provide a smooth enameled face from one compartment to the other to provide an easy cleansable lining surface throughout the entire refrigerator.

5. A refrigerator including, two lining portions, one adapted to form the food compartment of the refrigerator and the other adapted to form the ice compartment of the refrigerator, flanges integral with the lining portions forming openings in said lining portions adapted to fit in a manner to form a smooth telescopic joint between the portions, and an enameled surface over the entire part of each of said portions to provide a smooth, cleansable surface throughout the lining and at the telescopic joints.

In testimony whereof I affix my signature.

JOHN A. SEEGER.
